UNITED STATES PATENT OFFICE.

PETER J. QUINLAN, OF MARIETTA, OHIO.

GAS-BURNER.

1,164,210.

Specification of Letters Patent. Patented Dec. 14, 1915.

Application filed March 30, 1915. Serial No. 18,145.

To all whom it may concern:

Be it known that I, PETER J. QUINLAN, a citizen of the United States, residing at Marietta, in the county of Washington and State of Ohio, have invented a new and useful Gas-Burner, of which the following is a specification.

The device forming the subject matter of this application is a burner adapted to be employed for use in connection with gas and air, to produce a Bunsen effect.

The invention aims to improve the construction of the burner casing and its tubes, to provide novel means whereby the flow of air may be regulated, and to provide a novel means whereby the burner may be assembled with a furnace and boiler structure.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed, it being understood that changes in the precise embodiment of the invention herein disclosed can be made without departing from the spirit of the invention.

In the accompanying drawing:—Figure 1 shows the invention in side elevation, parts being broken away; Fig. 2 is a top plan; Fig. 3 is a cross section; Fig. 4 is a sectional elevation showing the device forming the subject matter of this application assembled with a furnace and a boiler.

In carrying out the present invention there is provided a box-like casing 1 comprising a bottom 2, sides 3, ends 4, a closure 5 having gas outlets 6, a top 7 spaced from the closure 5 to define a compartment 14, the ends 4 being extended as shown at 8 into engagement with the top 7 and ribs 9 being employed for connecting the closure 5 with the top 7 at intervals, thereby to define side air inlets 25.

Assembled with the top 7 are burner tubes 10 connected by webs 11, the tubes 10 preferably being disposed coaxially with respect to the gas outlets 6. As indicated at 12, the lower ends of the burner tubes 10 may project downwardly into the compartment 14. The ends 4 of the casing 1 may be provided with gas inlets 15, and the bottom 2

may be provided with a gas inlet 16 preferably located midway between the ends of the casing 1. It is to be understood that all of the gas inlets 15 and 16 may be used at once, or one or more of them may be employed, the remaining of the inlets being closed in any suitable manner.

In practical operation, gas is delivered into the casing 1 through the inlets 15 or 16, the gas passing upwardly through the outlets 6 and traversing the tubes 10, at the upper ends of which the gas is ignited. Air passes inwardly into the compartment 14 through the side inlets 25 and mingles with the gas in proper proportions before the mixture thus produced enters the tubes 10 at the upper ends of which the gas is ignited.

In Fig. 4 of the drawings there is shown a casing 17 supporting a boiler 18, the combustion space being indicated at 19 and a grate 20 being shown, the grate 20 serving to separate the combustion space 19 from the ash pit 21. The products of combustion pass through a stack 22. No novelty is claimed for the construction last above described, saving in so far as it may enter into combination with elements hereinbefore described and to be described hereinafter.

Mounted in the stack 22 is a damper 23 controlled by any suitable means indicated at 24.

In practical operation one or more of the structures shown in Figs. 1, 2 and 3 are placed beneath the grate 20, the burner tubes 10 projecting upwardly between the bars of the grate 20. A closure 35 is placed upon the grate, and thus air is prevented from drawing upwardly through the grate, independently of the burner tubes. By manipulating the damper 23, the draft through the burner tubes 10 may be adjusted, and in this manner, the amount of air applied may be regulated to a nicety. It is to be observed that in order to convert an ordinary coal burning furnace into a gas burning structure, no changes in the furnace are required. The burner tubes 10 are extended upwardly between the constituent parts of the grate 20 and the closure 35 is mounted in place on the grate bars. The furnace, therefore, may be readily converted from a coal burning structure into a gas burning structure, and with equal facility be reconverted from a gas burning structure into a coal burning one.

The structure forming the subject matter of this application is adapted to be used primarily under a low gas pressure, and it is so constructed that even with a low pressure, a perfect combustion will be effected.

Having thus described the invention, what is claimed is:—

In a device of the class described, a box-like casing including a closure; a top spaced 10 from the closure; end walls uniting the top with the closure; and a line of burner tubes 15 opening through the top, the closure having openings disposed below the burner tubes; the device being characterized by the fact that the extreme tubes of the line are disposed close to the end walls thereby to give the line a maximum length, that both ends of the casing and the intermediate portion thereof are provided with gas inlet openings

thus securing an adequate and even supply 20 of gas to the said extreme end tubes and to the inner tubes, that the lower ends of the tubes extend downwardly below the lower face of the top to receive gas from the openings in the closure, that the entire upper surface of the closure lies in a common plane thus to facilitate a draft of air through the downwardly extended ends of the tubes, and that supporting lugs connect the top and the closure intermediate the end walls, and 30 at the sides of the casing.

In testimony that I claim the foregoing as my own, I have hereto affixed my signature in the presence of two witnesses.

PETER J. QUINLAN.
